UNITED STATES PATENT OFFICE.

LÉON JUSSELIN, OF MOREAUVILLE, LOUISIANA.

MACHINE-GUN.

No. 861,467.

Specification of Letters Patent.

Patented July 30, 1907.

Application filed April 12, 1907. Serial No. 367,844.

To all whom it may concern:

Be it known that I, LÉON JUSSELIN, a citizen of the United States, residing at Moreauville, in the parish of Avoyelles and State of Louisiana, have invented certain new and useful Improvements in Machine-Guns, of which the following is a specification.

This invention relates to machine guns and more particularly to multi-barrel cannons.

One object of the invention is to provide a cannon embodying numerous barrels adapted to be brought successively into operative alinement with a suitable trigger mechanism for firing purposes.

Another object of the invention resides in the provision of a multi-barreled fire arm having the trigger mechanism including an element designed to lift the trigger of the trigger mechanism and also to perform the further function of a breech to hold the cartridge against displacement incident to concussion due to the explosion.

With the above and other objects in view the present invention consists in the combination and arrangement of parts hereinafter more fully described, illustrated in the accompanying drawings, and particularly pointed out in the appended claims, it being understood that changes may be made in the form, proportion, size and minor details without departing from the spirit or sacrificing any of the advantages of the invention.

In the drawings:—Figure 1 is a side elevation of the invention. Fig. 2 is a top plan view. Fig. 3 is a longitudinal sectional view. Fig. 4 is a front elevation of the shell. Fig. 5 is a rear elevation of the machine. Fig. 6 is a detailed view of the pawl adapted to prevent backward movement of the barrel. Fig. 7 is a diagrammatic view of a modified form of the use of the invention.

Referring now more particularly to the accompanying drawings, the reference character 1 indicates a base provided with uprights 2 and 3 connected at their upper ends by a cross piece 4 designed to aline with the upper end of the standard 5 secured at the forward end of the base for a purpose presently explained. The cross piece 4 is provided with a bearing depression 6 to coöperate with the bearing plate 7 clamped to the cross piece 4 in any suitable manner for the support of the trunnion 8 of the shell 9. The outer end of the shell 9 is supported by means of the trunnion 10 journaled in the bearing 11 of the upright 5, as clearly shown in Fig. 3.

The shell 9 is provided with a series of five bores 12 arranged concentrically with respect to the barrel and near the outer face of the latter. These bores are designed to be brought successively into alinement with the hammer 13 of the spring trigger 14 fixedly secured at one end to the frame, as indicated at 15. To bring the bores 12 successively into alinement with the ham-

mer 13 of the trigger 14 I provide the trunnion 8 with an operating wheel or equivalent 16. By operating the wheel or other operating means 16 in the direction indicated by the arrow in Fig. 5, the bores are brought successively into alinement with the trigger for firing purposes, and in order to prevent backward movement of the barrel, I provide the inner or major end thereof with a series of notches 17 which are engaged by the bifurcated upturned end 18 of the spring pawl 19 secured in any suitable manner to the base 1.

The character 20 indicates a series of cam blocks pivoted to the rear or major end of the barrel 9 by means of suitable pivots 21. These blocks 20 are arranged for coöperation one with each bore 12 and are pivotally mounted so that they may be turned to the position shown in dotted lines in Fig. 5, to permit of the insertion of a cartridge 22. After the insertion of the cartridge 22 the cam blocks 20 are turned so that one end may overlap the cap of the corresponding cartridge to hold the latter against displacement incident to concussion due to the explosion. The hammer head 13 of the trigger head 14 is designed to ride over the outer face of the cam blocks 20 when the barrel is rotated by the wheel or other operating means 16. In other words, assuming that one barrel or bore of the cannon has just been fired, the operating means is caused to continue rotating in the direction shown by the arrow in Fig. 5, which causes the hammer head 13 to ride upon the cam face of the corresponding block 20 resulting in the trigger being carried away from the rear or major end of the barrel until the hammer head reaches the higher end of the cam surface, when it will drop behind the corresponding cam block and, due to its spring nature, quickly strike the next cartridge and fire the same. The cam blocks 20 are so spaced as to permit the hammer head to drop between them successively for firing purposes, and it is obvious that as rapidly as the shell 9 is rotated, just as rapid will be the firing from the different bores of the barrel. The cam blocks 20 are held normally in engagement with the corresponding cartridges by means of a suitable spring 23 secured each at one end to the plate 24.

In Fig. 7 I illustrate a portion of a battle ship in plan to show the outline of a turret 24 mounted thereupon and provided with four of my improved multi-barreled cannons. In this connection, I will state that while the cannons 25 and 26 are being rapidly fired, the cannons 27 and 28 may be loaded for action to be put into commission as soon as the cannons 25 and 26 have been fired. It is obvious, therefore, that the turret may be rotated to bring the cannons 27 and 28 into the position of the barrels 25 and 26 for firing, although if desired, all barrels may be fired simultaneously.

What is claimed is:—

1. A fire arm of the character described comprising a frame, a shell rotatably mounted in the frame embodying

a plurality of barrels, spring controlled cam blocks pivotally mounted upon the inner end of the shell, one adjacent each barrel, one end of each block overlapping the head of the cartridge of the corresponding barrel to prevent displacement of the cartridge when exploded, a trigger arm having its hammer end arranged to ride upon the cam surface of said blocks and drop between the latter to engage the cartridges and explode them successively as the shell is rotated, and means whereby the shell may be rotated.

2. A fire arm of the character described comprising a frame, a shell rotatably mounted in the frame embodying a plurality of barrels, cam blocks pivotally mounted upon the inner end of the shell one adjacent each barrel, one end of each block overlapping the head of the cartridge of the corresponding barrel to prevent displacement of the cartridge shell when exploded, a trigger arm mounted upon the frame having its hammer end arranged to ride upon the cam surface of said blocks and drop between them to engage the cartridges and explode them successively as the shell is rotated, and means whereby the shell may be rotated.

3. A fire arm of the character described comprising a frame, a shell rotatably mounted in the frame, embodying a plurality of barrels, spring controlled cam blocks pivotally mounted upon the inner end of the shell, one adjacent each barrel, a trigger arm having its hammer end arranged to ride upon the cam surface of said blocks and drop between the latter to engage the cartridges and explode them successively as the shell is rotated, and means whereby the shell may be rotated.

4. A fire arm of the character described comprising a frame, a shell rotatably mounted in the frame embodying a plurality of barrels, pivoted cam blocks disposed upon the inner end of the shell, a trigger mechanism arranged to ride upon the cam surface of said blocks and drop between the latter to successively engage the cartridges of the barrels, of the shell, and means whereby the shell may be rotated.

5. A fire arm of the character described comprising a frame, a shell rotatably mounted in the frame embodying a plurality of barrels, spring controlled cam blocks pivotally mounted upon the inner end of the shell one adjacent each barrel, one end of each block overlapping the head of the cartridge of the corresponding barrel to prevent displacement of the cartridge shell when exploded, a trigger arm mounted on the frame having its hammer end arranged to ride upon the cam surface of said blocks and drop between them to engage the cartridges and explode them successively as the shell is rotated, and means whereby the shell may be rotated.

6. A fire arm of the character described comprising a frame, a shell rotatably mounted in the frame embodying a plurality of barrels, spring controlled cam blocks pivotally mounted upon the inner end of the shell one adjacent each barrel, one end of each block overlapping the head of the cartridge of the corresponding barrel to prevent displacement of the cartridge shell when exploded, a trigger arm mounted upon the frame having its hammer end arranged to ride upon the cam surface of said blocks and drop between them to engage the cartridges and explode them successively after the shell is rotated, and means whereby the shell may be rotated, the shell having notches

in its periphery, and a pawl secured to the frame for cooperation with said notches to prevent accidental backward movement of the shell.

7. A fire arm of the character described comprising a frame, a shell rotatably mounted in the frame embodying a plurality of barrels, movable cam blocks disposed upon the inner end of the shell, a trigger arm arranged to have its hammer head to ride upon the cam surface of said blocks and drop between the latter to successively engage and explode the cartridges of the barrels, and means whereby the shell may be rotated.

8. A fire arm of the character described comprising a frame, a shell rotatably mounted in the frame embodying a plurality of barrels, spring controlled elements pivotally mounted upon the inner end of the shell, one element adjacent to each barrel, one end of each element overlapping the cartridge of the corresponding barrel to prevent displacement of the cartridge shell when exploded, a trigger mechanism engaging said elements and adapted to operate between them to explode the cartridges, and means whereby the shell may be rotated.

9. A fire arm of the character described comprising a frame, a shell rotatably mounted in the frame embodying a plurality of barrels, spring controlled elements pivotally mounted upon the inner end of the shell, one element adjacent to each barrel, a trigger mechanism engaging said elements and adapted to operate between them to explode the cartridges, and means whereby the shell may be rotated.

10. A fire arm of the character described comprising a frame, a shell rotatably mounted in the frame embodying a barrel, pivoted cam blocks, a trigger mechanism including a hammer adapted to engage the outer face of the cam blocks and drop between the latter to explode the cartridges.

11. A fire arm of the character described comprising a frame, a shell rotatably mounted in the frame embodying a barrel, a spring controlled cam block mounted upon the shell, a trigger mechanism including a hammer adapted to engage said block and subsequently disengage the latter to explode the cartridge.

12. A fire arm of the character described comprising a rotatable shell embodying a barrel, a pivoted cam block mounted upon the shell, and a trigger mechanism including a hammer adapted to engage said block and subsequently disengage the latter to explode the cartridge.

13. A fire arm of the character described comprising a shell embodying a barrel, a spring controlled block mounted upon the shell, a trigger mechanism including a hammer adapted to engage said block and subsequently disengage the latter to explode the cartridge.

14. A fire arm of the character described comprising a rotatable shell embodying a barrel, a spring controlled pivoted block mounted upon the shell, a trigger mechanism including a hammer adapted to engage said block and subsequently disengage the latter to explode the cartridge.

In testimony whereof I have signed my name to this specification in the presence of two subscribing witnesses.

LEON JUSSELIN.
